CUTTING MACHINE

Charles H. Schurr, Cleveland, Ohio, assignor to
 The Lees-Bradner Company, Cleveland, Ohio,
 a corporation of Ohio

Application April 13, 1932, Serial No. 604,969

8 Claims. (Cl. 90—4)

This invention relates to cutting machines and is particularly applicable to hobbing machines, milling machines and the like.

An object of the invention is to provide an improved machine in which a plurality of units may be compactly grouped and attended by a single operator.

Another object of the invention is to provide an improved machine having few and simple parts.

Another object is to provide an improved machine which will be speedy in production and simple in operation.

Another object is to provide an improved machine which will be economical to manufacture and operate.

Another object is to provide an improved machine in which a number of units may be driven from a common source of power by simple transmission means.

Other objects will hereinafter appear.

The invention will be better understood from the description of one practical embodiment thereof illustrated in the accompanying drawing, in which:

Figure 1 is a side elevation, with parts broken away or in section, of an assembled machine having a number of units designed for hobbing gears;

Figure 2 is an enlarged, vertical, fragmentary, sectional view taken on the line II—II of Figure 1; and

Figure 3 is a fragmentary view showing a modified form of clutch actuating mechanism.

The apparatus shown comprises a stationary bed 1 upon which, and adapted to rotate about a vertical axis, is mounted a base or table 2. The central portion of the bed extends upwardly through the center of the base, as indicated at 3,

while the base has a downwardly extending central flange 4 fitting within the hollow of the bed and surrounding the projection 3.

The exterior of the bed is formed with an upturned flange 5 forming an annular trough 6 for the reception of cooling fluid and chips.

Keyed to the downwardly projecting flange 4 of the base is a worm wheel 7 with which meshes a worm 8 carried by a horizontal shaft 9 journalled within the bed and connected by means of a clutch 10 with an electric motor 11 or other driving means, so that the motor, through the worm and worm wheel, causes the base to rotate upon the bed.

Secured upon the upper end of the base or platform 2 are a number of machine units, each

shown as constituting in effect a hobbing machine. Each machine unit consists of a main frame 12 having at its bottom a horizontal flange 13 secured upon the upper surface of the base as by screws 14. The upper surfaces of the frames are connected to a ring 15 which serves to brace one frame to the other.

Formed upon the frame are two pairs of vertical ways 16 and 17, on one pair, 16, of which is slidably mounted a carriage 18 having formed upon it horizontal ways 19, and in these horizontal ways a slide or carrier 20 is arranged for translation.

Upon the carriage is journalled a horizontal shaft 21 having at one end a bevelled gear 22 meshing with a bevelled gear 23 splined to a vertical shaft 24, these two bevelled gears being housed within a projection 25 of the carriage.

The horizontal shaft 21 is itself splined to another horizontal shaft 26 journalled upon the slide, and the second horizontal shaft is provided at its end with a bevelled gear 27 meshing with a bevelled gear 28. The last mentioned gear is journalled in head 29 adjustably connected to the slide and arranged to be adjusted angularly about the axes of the horizontal shaft 26, and the head carries, within a housing-like extension 30, change gears 31 by which a spindle 32, also journalled in the head, may be driven from the vertical shaft at any selected speed. Upon this spindle is secured a hob or cutting tool.

The lower end of the vertical shaft 24 is journalled with a bracket 33 secured to the frame, the end projecting just beyond this bracket. Within the bracket, the shaft has keyed to it a bevelled gear 34 meshing with another bevelled gear 35 upon a horizontal stub shaft 36, also journalled in the bracket and provided at its other end with a spur pinion 37 which drives another spur pinion secured to the end of a horizontal shaft 38. The end of the vertical shaft is provided with one element 39 of a clutch, adapted to be engaged by a meshing element 40 splined to the upper end of a vertical shaft 41 journalled in the base or table. This clutch element is operated by a lever 42 extending to the outer side of the unit.

Keyed upon the lower end of shaft 41 is a pinion 43 rolling upon an internal gear 44 keyed to a circular flange 45 formed upon the bed.

Obviously, a train of gears can be interposed between shafts 41 and 24, as in general it will be found more advantageous to have the latter shaft rotate at a higher speed than would be the case if the shafts were directly joined to

gether. However, such gears have been omitted from the drawing for the sake of clarity.

The end of the horizontal shaft 38 adjacent the pinions is journaled in the bracket 33, while 5 the shaft itself extends through a housing 46 in which it is also journaled, being provided on its outer end with a change gear 47 meshing with a second change gear 48 upon a parallel shaft 49 also journaled in this housing.

10 The last mentioned shaft has formed upon it, within the housing 46, a skew gear and a worm 50. The worm meshes with a worm wheel 51 rotatably mounted upon a spindle 52 supported in bearings 53 within the housing.

15 Keyed to the worm wheel is a gear 54 with which mesh pinions 55 constituting part of a spur differential mechanism, these pinions in turn meshing with other pinions 56 of the differential mechanism, which latter engage a gear 57 keyed to the spindle.

20 These two sets of pinions are journaled within a drum-like ring 58 having on its exterior gear teeth engaged by the conjugate teeth of a gear 59 upon a vertical shaft 60 journaled in the 25 housing. This shaft passes downwardly to adjacent the upper surface of the base and is connected by change gears 61 to a vertical shaft 62 passing through the base and having at its lower end a pinion 63 meshing with the ring gear 64 30 keyed upon the exterior of cylindrical flange 45 of the bed.

Obviously, if it is not desired to use the machine to cut helical gears, this gear train may be interrupted and the shaft 60 locked against rotation, or the differential mechanism might be entirely omitted, the worm wheel being permanently secured to the spindle.

40 A hood 65 is attached to the upper end of the spindle and overlies the upper end of the housing, so that dirt, chips, and cooling fluid will be excluded from the interior of the housing.

45 The spindle 52 is intended to hold an arbor, or the like, by which the work is supported, and to rotate this in proper relation to the rotation of the tool upon the spindle 32 above described.

50 A skew gear 66 upon shaft 49 meshes with a skew gear 67 upon a transverse shaft 68, which drives, through change gears 69, a second transverse shaft 70. This shaft is provided with a 55 worm 71 meshing with a worm wheel 72 keyed to a cam drum 73. A groove 74 cut into the drum actuates a rod 75, having a roller fitting within the groove, connected to the carriage to move it up and down.

55 Upon the upper surface of the drum is formed a cam groove which by means of a lever is connected to rotate a vertical shaft 76 having at its upper end a pinion 77 meshing with a rack 78 formed on the slide for the purposes of moving 60 the slide upon the carriage.

65 Preferably the carriage is fed downwardly, and a counter weight is provided to compensate for the weight of the carriage, being connected thereto as by cables or a chain passing from sheaves supported upon the upper portion of the frame.

70 The means for moving the carrier and slide are not shown in great detail, as these are substantially the same as those illustrated in the co-pending application of Homer C. Warner and Charles H. Schurr, Serial No. 567,276, filed October 6, 1931.

75 In Figure 3 an automatic arrangement for operating the clutch 39 and 40 and a second clutch in the differential drive is illustrated. In this figure, lever 42' is extended inwardly as indi-

cated at 42a and provided on its inner end with a roller 42b. The lever is also connected to the movable element 60a of a second clutch, this element being arranged to mesh with a corresponding element 60b, both being interposed between shafts 61' and 61'' which correspond to shaft 61 of the embodiment illustrated in Figure 1. Upon projection 3' of the bed is formed at one point a bracket 3a provided with a downwardly inclined cam surface 3b which engages and depresses the roller when the unit reaches the operator's station. By depressing the inner end of lever 42', the cam disengages the clutch elements 39' and 40', 60a and 60b automatically, stopping all rotation of the spindles caused by the 10 drive either from pinion 43 or from pinion 63. A spring 42c raises the inner end of the lever, when it is released from the cam 3b, causing the engagement of both clutches. Obviously, lever 42' could be extended and provided with a hand grip 15 by which the operator could at any other point disengage the clutches.

The operation of the device is as follows:

The gears 31, 47, and 48 are chosen so that the relative rotation of the work and cutter spindles 25 are in any desired relation. Gears 69 are arranged to rotate the cams at a suitable speed. Gears 61, if the machine is to be used to cut helical teeth, are selected to operate the differential mechanism at a speed related to the helix 30 angle of the work to be produced.

Having adjusted all parts, the operator engages clutch 10, so that motor 11 causes the base to revolve upon the bed. As each unit reaches his station, he operates the handle 42 of the unit to 35 release its clutch (or clutches, if two are used), stopping or nearly stopping the rotation of the spindles. Of course, with the apparatus of Figure 3, this step is performed automatically and not by the operator.

40 The operator next places an arbor with a work gear secured upon it in the spindle 52 and brings the tail stock 79 down so that its dead-center 30 engages the arbor. As the unit passes the operator's station, the clutch or clutches operated by 45 the lever are engaged, either manually or by the cam mechanism, and, due to the motion of the table on the bed and the rolling of pinion 43 upon internal gear 44, power is transmitted to vertical shaft 24 and thence through horizontal shafts 21 50 and 26 to cutter spindle and by shafts 36, 38, and 49 to the worm driving the work spindle. The motion also is transmitted through gears 66, 68, and 71 to operate the cams by which the slide is 55 fed horizontally and the carriage vertically.

As the carriage moves vertically, the rotation on the table causes pinion 63 to roll upon ring gear 64, imparting an increment of rotation of spindle 52 through the differential mechanism, this increment corresponding to the helix angle 60 which is to be cut upon the work gear. When the cutter has travelled the entire distance through the blank and been returned to its starting position, the unit has again reached the operator's 65 station, so that he can remove the finished blank 70 a new work gear.

75 While I have described the illustrated embodiment of my invention in some particularity, obviously many others will readily occur to those skilled in this art, and I do not, therefore, limit myself to the precise details shown and described but claim as my invention all embodiments, variations, and modifications thereof coming within the scope of the appended claims.

I claim:

1. A hobbing machine comprising a bed, a frame rotatably carried thereby, means for rotating the frame upon the bed, a spindle journalled in said frame, a carriage slidable upon said frame in a direction parallel to said spindle, a slide movable on said carriage in a direction normal to said spindle, feed means for moving said spindles relative each other, a spindle journalled on said slide, a common drive shaft, gearing connecting said drive shaft to said second mentioned spindle, gearing connecting said drive shaft to said first mentioned spindle including a differential mechanism, feed means operated by said common drive shaft for moving said carriage upon the frame and said slide upon the carriage, and gearing between the bed and one element of the differential mechanism whereby said element is operated by the movement of the frame upon the bed independently of said feed means.
2. A hobbing machine comprising a bed, a frame rotatably carried thereby, means for rotating the frame upon the bed, a spindle journalled in said frame, a carriage slidable upon said frame in a direction parallel to said spindle, a slide movable on said carriage in a direction normal to said spindle, a spindle journalled on said slide, a common drive shaft, gearing connecting said drive shaft to said second mentioned spindle, gearing connecting said drive shaft to said first mentioned spindle including a differential mechanism, and a shaft connected to and driven by said drive shaft rotating two cams, connections between one cam and the carriage, connections between the other cam and the slide, and gearing between the bed and one element of the differential mechanism whereby said element is operated by the movement of the frame upon the bed.
3. A hobbing machine comprising a bed, a frame rotatably carried thereby, angularly disposed spindles carried by the frame and movable relative each other, a gear train connecting said spindles to rotate them at relatively fixed speeds, and including gearing actuated by the relative motion of the frame and bed to rotate one of the spindles relative the other, and feed means moving said spindles relative each other and independent of the relative motion of the frame and bed.
- 50 4. A hobbing machine comprising a bed, a frame rotatably carried thereby, angularly disposed spindles carried by the frame and movable

relative each other, a gear train connecting said spindles to rotate them at relatively fixed speeds and including a differential mechanism actuated by the relative motion of the frame and bed to rotate one of the spindles relative the other, and feed means moving said spindles relative each other and independent of the relative motion of the frame and bed. 5

5. A hobbing machine comprising a bed, a frame rotatably carried thereby, means for rotating the frame upon the bed, a carriage movably carried by the frame, a slide movable upon said carriage, a spindle journalled in the slide, a spindle journalled in the frame, a gear train between said spindles including a differential mechanism, 15 one element of each differential mechanism being rotated by movement of the frame on the bed, and feed means for moving said carriage.

6. A hobbing machine comprising a bed, a frame rotatably carried thereby, means for rotating the frame upon the bed, a carriage movably carried by the frame, a slide movable upon said carriage, a spindle journalled in the slide, a spindle journalled in the frame, a gear train between said spindles including a differential mechanism, 25 one element of said differential mechanism being rotated by movement of the frame on the bed, feed means for moving the carriage, and feed means for moving the slide upon the carriage, both of said feed means being driven by said gearing. 30

7. A hobbing machine comprising a bed, a frame rotatably carried thereby, spindles carried by the frame and movable relative each other, a gear train connecting said spindles to rotate them at relatively fixed speeds, and including gearing 35 actuated by the relative motion of the frame and bed to rotate one of the spindles relative the other, and feed means moving said spindles relative each other and independent of the relative motion of the frame and bed. 40

8. A hobbing machine comprising a bed, a frame rotatably carried thereby, spindles carried by the frame and movable relative each other, a gear train connecting said spindles to rotate them at relatively fixed speeds and including a differential mechanism actuated by the relative motion of the frame and bed to rotate one of the spindles relative the other, and feed means moving said spindles relative each other and independent of the relative motion of the frame and bed. 45 50

CHARLES H. SCHURR.
